UNITED STATES PATENT OFFICE.

HERBERT WILSON, OF TOLEDO, OHIO, ASSIGNOR TO THE DURA COMPANY, OF TOLEDO,
OHIO, A CORPORATION OF DELAWARE.

DESIGN FOR A SWITCH PLATE.

Application filed January 28, 1924. Serial No. 8,454. Term of patent 7 years.

To all whom it may concern:

Be it known that I, HERBERT WILSON, a citizen of the United States of America, residing at Toledo, in the county of Lucas and State of Ohio, have invented a certain new, original, and ornamental Design for a Switch Plate, of which the following is a specification, reference being had therein to the accompanying drawings, forming part thereof, in which—

Fig. 1 is a plan view of a switch plate showing my new design; and Figs. 2 and 3 are respectively side and end elevations thereof.

I claim:

The ornamental design for a switch plate, substantially as shown.

HERBERT WILSON.
